W. C. Simonds

UNITED STATES PATENT OFFICE.

EDWARD JOY MORRIS, OF PHILADELPHIA, PENNSYLVANIA.

DESIGN FOR A TRACK OR WAY FOR AMUSEMENT-RAILWAYS.

SPECIFICATION forming part of Design No. 34,293, dated March 26, 1901.

Application filed February 26, 1901. Serial No. 49,009. Term of patent 14 years.

To all whom it may concern:

Be it known that I, EDWARD JOY MORRIS, a citizen of the United States, residing in the city of Philadelphia, in the county of Philadelphia and State of Pennsylvania, have invented and produced a new and useful Design for a Track or Way for an Amusement-Railway, of which the following is a specification, reference being had to the accompanying drawings, forming part thereof.

Figure 1 is a view in perspective of a track for an amusement railway showing my new design.

Figure 2 is a plan view of the same.

As shown in the drawings, the leading or material feature of my design consists of a track for an amusement railway, formed as an endless structure, disposed in a plurality of superposed spiral convolutions *a*, and in a loop *b* of U-shaped plan connective of the upper and lower convolutions, the bight of which loop extends out beyond the convolutions.

The convolutions are in plan of elongated form, and their respective side portions extend inward or converge toward each other, that is to say, each elongated convolution consists of two curved regions one at each of its respective ends, and two side members connective of said curved regions, said side members each consisting of a relatively long straight course and a relatively short and quite abruptly curved course.

The said side members make connection with a given curved end region, the one

through its relatively long straight course, which merges into said curved region at that point of the latter which is at the greatest distance from the median line of the convolution, and the other through its shorter course, 40 the portions of the respective side members which most closely approach said median line being thus opposite different portions of said line.

The respective convolutions are disposed 45 the one above the other, and, of course, merge gradually the one into the other.

The loop *b* of U-shaped plan connective of the lowermost and uppermost convolutions, is as to the leg *c* which merges into the lowermost convolution, and also as to the bight *f*, approximately horizontal, and is as to the leg *d* which merges into the uppermost convolution inclined from the ground level to said uppermost convolution. 55

A series of dips *e* are formed in the track one in the straight course of each of the side members and one in the leg *c* of the U-shaped loop.

Having thus described my invention, I 60 claim—

The design for a track or way for an amusement railway, as herein shown and described.

In testimony that I claim the foregoing as my invention I have hereunto signed my name 65 this 13th day of February, A. D. 1901.

EDWARD JOY MORRIS.

In presence of—

S. SALOME BROOKE,
THOMAS K. LANCASTER.
